CLAIM

The ornamental design for a multi-media phone, as shown and described.

DESCRIPTION

FIG. 1 is a perspective view of a multi-media phone showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of another embodiment of a multi-media phone showing our new design;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

In FIGS. 7 and 14, the broken lines represent unclaimed boundaries of the claimed design. The broken lines and the unshaded region that is bounded on two sides by broken lines and on two sides by solid lines forms no part of the claimed design.
